UNITED STATES PATENT OFFICE.

GEORGE A. SHORES, OF CEDAR RAPIDS, IOWA, ASSIGNOR TO SHORES-MUELLER COMPANY, OF CEDAR RAPIDS, IOWA, A CORPORATION OF IOWA.

DESIGN FOR A MEDICINAL TABLET.

56,478.

Specification for Design.

Patented Oct. 26, 1920.

Application filed April 8, 1920. Serial No. 372,372. Term of patent 14 years.

To all whom it may concern:

Be it known that I, GEORGE A. SHORES, a citizen of the United States of America, and a resident of Cedar Rapids, Linn county, Iowa, have invented a new, original, and ornamental Design for Medicinal Tablets, of which the following is a specification, reference being had to the accompanying drawing, forming part thereof.

I claim:

The ornamental design for a medicinal tablet, as shown.

Signed at Cedar Rapids, Ia., this 13th day of March, 1920.

GEORGE A. SHORES.
